UNITED STATES PATENT OFFICE.

THEODORE KORN BRODT, OF CHICAGO, ILLINOIS.

AIR-SHIP.

No. 866,665.

Specification of Letters Patent.

Patented Sept. 24, 1907.

Application filed July 8, 1907. Serial No. 382,668.

To all whom it may concern:

Be it known that I, THEODORE KORN BRODT, a citizen of the United States, residing at Chicago, in the county of Cook and State of Illinois, have invented 5 certain new and useful Improvements in Air-Ships, of which the following is a specification, reference being had to the accompanying drawings.

My invention relates to improvements in airships and more particularly to the means for propelling and 10 steering them.

The object of the invention is to provide a simple and effective means whereby an airship or balloon may be propelled and steered or guided in any direction by one or more blasts of air created by propellers 15 and suitably directed by a steering mechanism.

With the above and other objects in view the invention consists in the novel construction and the combination of parts hereinafter described and claimed, and illustrated in the accompanying drawings, in which 20

Figure 1 is a vertical longitudinal section through my improved airship; Fig. 2 is a top plan view; Fig. 3 is an end elevation; Fig. 4 is a detailed section on an enlarged scale through the rear propeller casing and 25 the attached parts of the invention and Fig. 5 is a plan view of a slightly modified form of the invention.

In the drawings 1 denotes the car or body of the improved airship, which is suitably suspended as at 2 from a gas bag or balloon 3 preferably of elliptical 30 form. The gas bag 3 comprises a casing or covering 4 arranged upon a suitable frame 5, and extending longitudinally through its center is a tube 6 which is open at both ends to provide a cylindrical chamber or passage 7 through the gas bag. The tube 6 consists 35 of a covering 8 arranged upon a supporting frame 9, and it is united at its ends to the ends of the bag 3 by the casings 10, 11 of two rotary air propellers 12, 13. These casings 10, 11 are of cylindrical form and have at their inner ends right angularly disposed 40 attaching flanges 14, 15 to which the bag 3 and tube 6 are respectively secured by means of bolts or the like 16 and clamping rings or bands 17, as clearly shown in Fig. 4.

The fans or propellers 12, 13 may be of any suitable 45 form and construction and their shafts 18 are journaled in suitable bearings arranged in spiders 19 in said casings 10, 11. Upon the outer end of each of the propeller shafts 18 is arranged a pulley 20 which is connected by a belt 21 to a larger pulley 22 arranged 50 upon one end of a shaft 23 extending longitudinally in the car 1 and suitably connected to an engine or motor 24 of any description. It will be seen that when the latter is operated it will drive the fans and thereby create a strong current or draft of air through 55 the chamber 7 in the direction of the arrow in Fig. 1. The belt 21 at the rear of the airship passes through

a slot 25 formed in an extended portion 26 of the rear propeller casing 11, on which portion is secured by bolts 27 and a clamping ring 28, a tubular steering element 29. The latter forms a continuation of the 60 air chamber or passage 7 and is so constructed that it may be turned or swung in any direction so that the blast of air passing through said chamber may be so directed as to steer the airship.

While the steering tube or element 29 may be constructed and operated in any suitable manner I preferably make the same resilient and provide means whereby it may be bowed in any direction as indicated in dotted lines in Figs. 1 and 2. As shown the steering tube is composed of an outer covering 30 70 arranged upon a cylindrical spiral frame 31 constructed of resilient metal and having at its outer end a reinforcing band 32. The resiliency of the frame 31 is such that the steering tube will project normally in a rearward direction in longitudinal alinement 75 with the chamber or passage 7.

For the purpose of bowing or swinging the tube 29 in different directions to direct the blast of air so as to cause the ship to move in the desired direction, I preferably employ four or more ropes, cables or other 80 flexible elements 33, 34, 35, 36. These cables have their outer ends attached to eyes arranged on the reinforcing band or collar 32 at equi-distant points, and their opposite ends are passed through suitable guides 34 suitably arranged on the bag or body 3. 85 The lower ends of said operating cables extend down to the car 1 and any suitable means may be provided so that the operator may readily control them. It will be noted that by properly manipulating one or more of these cables, the steering tube may be swung 90 or bowed in any direction so as to discharge the blast of air created in the chamber or passage 7 by the propellers 13, in such direction and thus permit the ship to be readily steered or guided.

In Fig. 5 of the drawings I have shown the tube 6 95 which forms the air passage or chamber 7 arranged between two gas bags 3^a, 3^b instead of within a single bag as above described and shown in the other figures of the drawings. It will be understood that the tube 6 may be arranged at any suitable point upon 100 the ship and one or more of them may be employed.

Having thus described my invention what I claim is:

1. In an airship, a chamber or passage, cylindrical casings arranged at the ends of said chamber, propellers arranged in said casings for creating a blast of air through the chamber, an annular flange projecting radially from one of said casings adjacent to its outer end, a coil spring engaged with said end of the last mentioned casing and abutting against said flange, a flexible covering arranged upon said spring and adapted to form a tubular, blast-directing element, a ring surrounding the inner ends of the covering and spring, fastenings for clamping said band covering and spring to the outer end of said casing, a reinforcing ring or band arranged upon the outer end of the spring and its

- covering and means for swinging the said element in different directions, substantially as and for the purpose set forth.
2. In an airship, a gas bag, a tube extending through the bag, cylindrical casings arranged at the ends of the tube and bag and serving to unite them, and propellers arranged in said casings for creating a blast of air through said chamber, substantially as set forth.
3. In an airship, a gas bag, a tube extending through the bag, cylindrical casings arranged at the ends of the tube and bag, said casings having at their inner ends right angularly disposed flanges, rings or bands for clamping the

ends of said body and said tube to said flanges, propellers arranged in said casings for creating a blast of air through said tube, a flexible, tubular steering element connected to 15 the outer end of one of said casings and means for swinging said element in different directions, substantially as and for the purpose set forth.

In testimony whereof I hereunto affix my signature in the presence of two witnesses.

THEODORE KORN BRODT.
